UNITED STATES PATENT OFFICE.

CHARLES STUART CHRISTIE AND ERNEST A. POTTER, OF ESPANOLA, ONTARIO,
CANADA.

APPARATUS FOR DRYING PAPER.

Application filed October 2, 1922. Serial No. 591,807.

To all whom it may concern:

Be it known that we, CHARLES STUART CHRISTIE and ERNEST A. POTTER, subjects of the King of Great Britain and of the 5 United States, respectively, and both residing in Espanola, District of Sudbury, Province of Ontario, Canada, have jointly invented certain new and useful Improvements in Apparatus for Drying Paper, of 10 which the following is a specification.

Our invention relates to improvements in apparatus for drying paper, and the principal objects of our invention are: first, to dispense with the use of the dryer felts; 15 second, to utilize otherwise waste heat from the dryer rolls to heat air drawn from the machine room for the purpose of drying the paper; third, to simultaneously dry both sides of the web of paper (a) by direct application of the web to the dryer rolls and (b) by currents of heated air flowing longitudinally of certain of the dryer rolls, and in the following specification we shall describe our preferred form of apparatus, and 20 what we claim as new will be set forth in the claims forming part of this specification. Fig. 1 is, in part, a side elevation of our preferred form of apparatus, certain parts being shown in vertical longitudinal section. 25 The apparatus is shown as mounted within a suitable building. Fig. 2 is a vertical section on the line 2—2, Fig. 1. Fig. 3 is an elevation of the dry end of the apparatus, with certain parts broken away and shown 30 in section. Fig. 4 is a plan view of the apparatus, shown in Fig. 1, with certain parts shown in horizontal section. Fig. 5 is a fragmentary view of one of the dryer rolls, showing the sheave for the ropes of the automatic back tender, and Fig. 6 is a central longitudinal section through one end of one 35 of the dryer rolls, showing more particularly the sheave for the ropes of the automatic back tender, in relation to the stub-shaft of the dryer roll.

In the drawings, like characters of reference refer to the same parts.

It is now common in the art to utilize heated dryer rolls, around which pass felts. 50 One of the functions of the felts is to absorb moisture from the web of paper and so assist the dryer rolls in performing their function, but when felts are used, felt dryers must also be used. Now since we dispense with the felts, we consequently dis-

pense with the felt dryers, and the consequence is that we can reduce the cost of manufacture of machines of this class much below that now quoted. Another important function performed by the felts is that of carrying the web of paper through the machine and maintaining it in contact with the dryer rolls, but we have found that when we utilize the automatic back tender, we can dispense with the felts, and the felt dryers, 60 because by the time the web of paper reaches the ponye dryer, its tensile strength is sufficient to permit it to be "threaded" through the machine through the medium of the automatic back tender. In "threading" the 65 web through this machine, the attendant need only wrap the tail end of the web around the ropes of the back tender, which will function in a manner well-known to ultimately draw the web through the machine. The tail of the web used to draw the 70 rest of the web through the machine is torn off when the web is properly positioned on the dryer rolls.

In machines of this class, the dryer rolls 75 are exposed to the air in the machine room at each end, and frequently cold draughts of air come in contact with these exposed ends, with the result that the temperature within the rolls at these ends is reduced, and 80 a uniform drying of the web of paper will not be had. Now we close in the dryer rolls and otherwise control the direction of movement of currents of heated air through the 85 housing or casing for the machines to effect 90 the purpose in view.

In machines using felts, relatively little 95 of the outer side of the web is exposed to the air, and the currents of air that come in contact with the exposed side of said web 100 of paper vary in temperature and direction, particularly in winter time in this latitude, portions of the machine be located opposite door-ways leading from rooms where the 105 temperature is considerably lower than that obtaining in the paper machine room. The balance of the outer surface of the web of paper is blanketed by the felts, and the result is that these portions of the web of paper can only directly yield up the moisture according to the absorbing capacity of that portion of the felts in contact therewith.

Dryer rolls are usually mounted in horizontal rows, one above the other, the dryer 110

rolls in each row occupying a staggered position in relation to the dryer rolls above or below, and the consequence is that pockets extending longitudinally of the rolls and located between each pair of dryer rolls in the lower row, and roofed, so to speak, by a dryer roll in the upper row, are formed. Now our object is to force draughts of heated air through these pockets so as to prevent stagnation therein of the water vapor and so facilitate drying.

Since we do not require to use felts, we can operate with a considerably lower steam pressure within the dryer rolls, and thus effect economy in fuel.

Our preferred form of apparatus embodies dryer rolls A and B located in upper and lower rows, as shown clearly in Fig. 1, and in staggered relationship as before-mentioned. These dryer rolls may be of any desired construction, and a suitable way of supporting them is to journal the stub-shafts C thereof in suitable standards D. The stub-shafts E have bearing in the standards F. The stub-shafts E are in the form of pipes, and by means of the usual pipes G and couplings, steam is conveyed to and from said dryer rolls through the medium of the pipes H. Of course there is nothing new in the parts just described. The said dryer rolls are driven in any suitable manner as by means of the meshing gears I which are coupled to the stub-shafts E. J is the pit which is formed by the side and end walls 2 and the floor 3, which walls extend up to the floor 4 of the building 5, which floor is provided with an opening leading into the pit J. 6 is a hood or roof located above the dryer rolls, preferably gable-shaped. The hood or roof 6 is provided with side walls 7 which extend down to the floor 4, and therefore these side walls co-operate with said hood 6 and walls 2 and the floor 3 of the pit to form a housing for the dryer rolls. These side walls may embody movable panels such as sliding doors 8 to permit access to the ends of the dryer rolls. These panels or sliding doors may be of any well-known construction, and they are merely diagrammatically illustrated in the drawings. Extending longitudinally of the hood or roof 6 at each side thereof, are conduits 9 which open into conduit 10 located at the dry end of the machine. Located underneath the hood or roof 6 are a plurality of conduits 12, spaced apart, which open into the conduits 10 and 11.

Extending along the sides of the machine are conduits 13 and 14 which are coupled in any suitable manner (see Figs. 2 and 3) to a conduit 15 which opens into a fan or blower chamber 16 which communicates with the conduit 11.

The inner sides of the conduits 13 and 14 are apertured to permit outlet pipes 17 to

be connected therewith, which pipes extend through apertures formed in the walls 2, into the pit J.

The automatic back tender is of a well-known construction, and it comprises a plurality of pulleys 18 suitably mounted, over which pass the ropes 19. These ropes pass around sheaves 20 suitably associated with one end of the dryer rolls, and the function of said automatic back tender is to thread the paper, in a manner already known around the various dryer rolls. The wet paper 21 enters the machine at the wet end through the opening 22, which opening is located between the wall 23 of the conduit 11 and the closure member 24 carried by the floor 4, and located outside the pony roll 26. Upon referring particularly to Fig. 1 the paper 21 will be seen passed around the various dryer rolls.

Steam usually at a pressure from 12 to 14 pounds per square inch is passed into the dryer rolls through the tubular stub-shafts E, and the heat therefrom expels the moisture content from the web of paper, and one of the objects of our invention is to utilize the otherwise waste heat escaping from said dryer rolls to heat currents of air drawn from the machine room to dry the paper, and to remove water-vapor from the pockets 27 formed by the space between the various dryer rolls in the lower row and the staggered dryer rolls in the upper row, when the web of paper is going through the machine.

Any suitable blower or fan 28 is mounted within the chamber 16, and suitably driven. Now since the conduits 9 are provided with apertures 29, air is drawn from the machine room by the action of the fan or blower 28 through these conduits into the conduit 10, and thence through the conduits 12 into the conduit 11 and thence through the conduits 13 and 14 and outlet pipes 17 into the pit J. As the air passes through the conduits 12, the temperature thereof is raised very considerably by reason of the heat within the housing for the dryer rolls, and therefore when it escapes into the pit J it serves the purpose of hastening the drying of the web of paper.

It will be observed upon referring particularly to Fig. 4 that the outlet pipes 17 are in a staggered position in respect of the sides of the machine, and are located approximately underneath the pockets 27 (see Fig. 1). The result is that the water-vapor-laden air in said pockets is moved longitudinally of said dryer rolls to the ends thereof, between which ends and the side walls 7 (see Fig. 2) it escapes into the upper portion of the housing for said dryer rolls, and thence naturally, or by mechanical means it is exhausted through the ventilators 30 which open through the hood or roof 6.

We prefer to divide the conduit 10 by

means of a partition *a* (see Fig. 4) so as to equalize the currents of air drawn through the conduits 12 at each side of the machine.

The conduits 13 and 14 are preferably 5 tapered (see Fig. 1) so as to equalize the air currents received in the pit *J*, which currents are utilized to remove the vapor from the pockets 27.

From what has been set forth it is clear 10 that we control sufficiently the path of various air currents through the housing for the dryer rolls to effect the purpose in view. The opening 22, and the opening *b* and *c* at the wet and dry ends of the machine 15 are not sufficient to interfere with the attaining of the object we have in view.

In winter time in order to keep the roof *d* of the building dry we make use of the usual conduit *e* forming part of the heating 20 system.

Upon referring particularly to Fig. 1, it is self-evident that we simultaneously ultimately heat-treat both surfaces of the web of paper, and in such a manner as to 25 remove in the quickest manner the vapor content thereof. The currents of hot air flowing longitudinally of the dryer rolls in the lower row, and through the pockets 27 come directly in contact with the other 30 surface of large areas of the web of paper, while the inner surface of the major portion of said areas, is directly in contact with the dryer rolls. Since the undersides of the dryer rolls in the top row, which form 35 the roofing, so to speak, of the pockets 27, are exposed directly to the flowing currents of hot air, the moisture adhering to these exposed sides will be largely carried away by these currents of air, thus presenting 40 frequently relatively dry surfaces of the heated rolls to the web. In effect, the currents of hot air flowing through the pockets 27 perform the function performed by the felt dryers before mentioned.

45 Various changes in details of construction may be effected without departing from the spirit of our invention.

What we claim is:

1. An apparatus of the class set forth 50 comprising a plurality of driven heated

dryer rolls around which the web of paper to be dried is passed; a ventilated housing for said dryer rolls adapted to receive the heat escaping from said dryer rolls; a plurality of conduits in said housing and adapted to be heated by the heat escaping from said dryer rolls; means to permit air to pass from the machine room into and through said conduits in said housing so that the temperature of said air may be 60 raised, and means whereby said heated air may be passed into said housing and below said dryer rolls, for the purpose set forth.

2. An apparatus of the class set forth comprising a plurality of driven heated dryer 65 rolls around which the webs of paper to be dried is passed; a ventilated housing for said dryer rolls; apertured conduits adapted to receive air from the machine room; conduits at the ends of said housing, into one 70 of which passes the air from said first-mentioned conduits; a plurality of conduits connecting together the conduits located at the ends of said housing, and located within said housing and above said heated dryer 75 rolls, and means communicating with the conduit at the wet end of the machine, adapted to convey said heated air into said housing and below said dryer rolls, for the purpose set forth.

3. An apparatus of the class set forth comprising a plurality of driven heated dryer rolls around which the web of paper to be dried is passed; a ventilated housing for said dryer rolls; apertured conduits 85 adapted to receive air from the machine room; conduits at the ends of said housing, into one of which passes the air from said first-mentioned conduits; a plurality of conduits connecting together the conduits located 90 at the ends of said housing, and located within said housing and above said heated dryer rolls; a blower or fan connected with the conduit at the wet end of the machine, and a pair of conduits located at the sides of 95 said housing and adapted to convey said heated air into said housing and underneath said dryer rolls.

CHARLES STUART CHRISTIE.
ERNEST A. POTTER.
